LUBRICATED SYRINGE

Allan P. Bloxsom, Houston, Tex.

Application November 25, 1950, Serial No. 197,620

5 Claims. (Cl. 128—218)

1

This invention relates to syringes which are used for hypodermic, irrigation, and other purposes.

In conventional syringes much difficulty has been encountered due to the sticking of the plunger in the barrel of the syringe. This is particularly true in the giving of large amounts of fluids where ordinarily a stock of syringes are necessary due to the sticking of the plunger and barrel of the syringe and the consequent need for substituting a second or more syringes. Moreover, considerable difficulty is encountered in giving transfusions in small veins because of the possible necessity for withdrawing the needle out of the vein before completion of the transfusion and the attendant difficulties encountered in re-finding the small vein.

Accordingly, it is a prime object of my invention to provide a syringe which is lubricated and thereby eliminate sticking of the plunger in the barrel.

It is a further object of my invention to provide a syringe in which large amounts of fluid may be given by a single syringe thereby avoiding the necessity of using a stock of several syringes.

It is a still further object of my invention to provide a syringe which is lubricated and yet may be easily cleansed and sterilized.

It is yet a further feature and object of my invention to provide a syringe in which the giving of large amounts of fluids is less tiring or burdensome to the operator of the syringe than is the case in using conventional syringes.

It is a still further object of the present invention to provide a syringe which has a substantially constant pressure feed.

It is yet a further object of my invention to provide a series of reservoirs in the inner wall of the barrel of the syringe in order that a wetting agent will constantly wet the plunger and provide a uniform film between the plunger and the barrel, thereby maintaining a constant operating pressure.

It is still a further object and feature of my invention to provide a syringe which eliminates the need of changing the syringe in giving transfusions in small veins and, accordingly, reduces the possibilities of withdrawing the needle from the vein and the attendant difficulties of inserting the needle back into the small vein.

In accordance with the present invention the lubrication for the plunger which eliminates sticking thereof may be provided by self lubrication of the medicament fluid being used in the syringe. That is, in the giving of glucose or an

2

intravenous anesthesia, the glucose or anesthesia may be utilized as the lubricant. However, the lubrication may be furnished by a fluid foreign to the medicament fluid being used in the syringe; for example, in the giving of blood in transfusions, saline, glucose, or Hartmann's solution may be used to advantage as the lubricating fluid.

Accordingly, it is a further feature and object of my invention to provide a syringe in which the plunger may be lubricated by either the medicament fluid being used in the syringe or by a lubricating fluid foreign to that being used in the syringe.

Other and further objects and features will be apparent from the following description, which is by way of example, taken in connection with the accompanying drawing, in which:

Fig. 1 is a side view, with parts broken away, of a syringe constructed in accordance with the invention,

Fig. 2 is a cross-sectional view taken along the line 2—2 of Fig. 1, looking in the direction of the arrows,

Figs. 3, 4, 5 and 7 are fragmentary side views, with parts broken away, illustrating alternative embodiments of syringes constructed in accordance with my invention, and

Fig. 6 is a cross-sectional view taken along the line 6—6 of Fig. 5, looking in the direction of the arrows.

Referring now to the drawing, where like character references refer to like parts throughout the several views, the reference character 10 indicates the barrel or piston chamber defining a reservoir chamber having the plunger or piston 12 movable therein. Any preferred grip 14 for the plunger may be utilized and I have illustrated a conventional head member 16 for the barrel in which a conventional needle may be secured. In order to aid in the use of the syringe the finger stop members 18 in the form of a flange are provided integral with the outer end of the barrel or piston chamber 10.

The syringe is conventionally formed of glass but may be formed of any suitable material. The above described elements of the syringe are typical and conventional and are merely referred to for the purposes of disclosure.

The present development relates to the provision of lubricant holding reservoir recesses, generally referred to by the numeral 20, near the outer end of the barrel or piston chamber 12. As illustrated in Fig. 1 the lubricating recesses comprise a plurality of grain or ellipsoidal shaped recesses, viewed in cross-section, defining two cir-

cumferential rows of recesses. The lubricating recesses are better seen in Fig. 2. Thus, when the plunger or piston 12 is moved outwardly, as when filling the reservoir defined by the barrel and plunger head, the outer surface of the plunger or piston will tend to dry and upon moving the plunger 12 inwardly, the latter will be wetted by the fluid trapped in the recesses 20 thereby lubricating the plunger 12 as it is moved in the piston chamber or barrel 10.

While the lubricant holding reservoirs or recesses 20 in the inner wall of the barrel or the piston chamber 10 are illustrated as defined generally by two circumferential channels, one or more of such channels may be utilized. Moreover, the recesses 20 may be defined by an almost unlimited variety of grooves or indentations. For example, Fig. 3 illustrates substantially circular recesses 22 in the general form of spaced circumferential channels. Fig. 4 illustrates a plurality of diagonal grooves 24 defining generally a pair of circumferential channels. Fig. 5 illustrates spaced circumferential rings 26 as the circumferential grooves, and Fig. 7 illustrates the grooves as V-shaped, viewed in cross-section, rings 28.

Thus it is manifest that the recesses provided in the inner wall of the piston chamber 10 may be defined by a variety of forms; however, it is preferable that these lubricant retaining recesses or reservoirs be positioned close to the outer end of the barrel 10 and, while only one such series of recesses is satisfactory, any number may be utilized. Moreover, instead of circumferential channels or rings, a series of recesses or the like may be inclined to the axis of the piston chamber; however, in such event, the lubricant channels 20 should not extend along the inner face of the barrel 10 in a longitudinal direction for too great a length because of possible leakage of fluid past the piston 12.

In use, for example in the giving of fluid medicament such as glucose or an intravenous anesthesia, the plunger 12 may be withdrawn substantially to the outer end of the barrel 10 thereby filling the latter with such fluid and thereby filling the recesses 20. In giving the fluid the piston 12 will be urged inwardly thereby expelling the fluid and after the leading end of the piston 12 has passed one or more of the recesses 20, the fluid therein will be retained therein and will wet the plunger 12 thereby lubricating it and avoiding sticking of the plunger 12 and the cylinder 10. In addition a substantially constant pressure feed for the syringe will be provided.

If desired, a fluid foreign to the fluid medicament being given may be utilized as the lubricant as, for example, in the giving of blood in transfusions, the syringe may be filled with a suitable lubricating fluid, such as saline, glucose or Hartmann's solution and the solution expelled

and the piston cylinder or barrel 10 may then be filled with blood and the transfusion given, the lubricating fluid remaining in the recesses and providing lubrication for the plunger.

It seems manifest that a syringe constructed in accordance with the present invention would be easy to sterilize and keep clean. The cleansing and sterilizing of syringes consumes some little time and in some instances is quite troublesome and a syringe constructed according to the present invention is advantageous in this respect. However, the principles of the present invention may be applied to any of the conventional syringes. Moreover, it seems manifest that the reservoirs 20 for housing fluid to provide the lubricating function may assume an unlimited variety of forms.

Accordingly, while several embodiments of the syringe are shown and described herein, it is obvious that the principles of the present invention may be applied to any conventional syringe and that various changes may be made in the construction and arrangement of parts without departing from the spirit of the invention or the scope of the appended claims.

I claim:

1. A syringe comprising a barrel, a plunger of substantially constant diameter movable in the barrel, and recesses in the barrel adapted to retain fluid and lubricate the movable plunger.

2. A syringe comprising a barrel, a plunger of substantially constant diameter slidably in the barrel, and grooves in the barrel adapted to retain fluid and lubricate the movable plunger.

3. A syringe comprising a barrel, a plunger of substantial constant diameter movable in the barrel, and reservoir recesses in the barrel disposed near its outer end adapted to retain fluid and lubricate the plunger.

4. A syringe comprising a barrel, a plunger of substantial constant diameter movable in said barrel, and grooves in said barrel defining at least one circumferential channel near the outer end of said barrel adapted to retain fluid and lubricate the plunger.

5. A syringe comprising a barrel, a plunger of substantial constant diameter movable in the barrel, and reservoir means in an inner wall of the barrel adapted to retain a wetting agent to provide a fluid film between adjacent surfaces of the barrel and the plunger thereby providing a constant operating pressure.
